UNITED STATES PATENT OFFICE.

ARTHUR WRENN LAMBERT, OF CROYDON, ENGLAND.

MEANS FOR SUPPORTING SHELVES AND ANALOGOUS PURPOSES.

1,400,960.

Specification of Letters Patent. Patented Dec. 20, 1921.

Application filed February 8, 1921. Serial No. 443,353.

To all whom it may concern:

Be it known that I, ARTHUR WRENN LAMBERT, a subject of the King of Great Britain and Ireland, residing at Croydon, in the county of Surrey, England, have invented Improvements in or Relating to Means for Supporting Shelves and Analogous Purposes, of which the following is a specification.

- 10 The principal object of the present invention is to provide improved means for enabling shelving, brackets or equivalent members intended to carry, support or display books or other objects, to be adjusted 15 in position positively with a more ample gradation than has heretofore been possible taking into consideration a given initial pitch of positioning regions. To this end the invention consists broadly in providing 20 a support with a plurality of positioning regions differing in pitch from that of another set of positioning regions on a member to be supported, and employing a connector, separate from both the support and 25 member to be supported, adapted to couple them together with any companion pair of positioning regions in register. In this way the minimum adjustment obtainable as also 30 the value of a series of adjustments taken collectively is less than the pitch of the positioning regions of either the support or supported member, the arrangement functioning after the manner of a vernier.
- Other features of the invention consist 35 in the provision of means as aforesaid in which the positioning regions are so constituted that they exert a locking action upon the connector tending to prevent accidental disconnection between the support 40 and supported member; constructions in which the connector, after assemblage cannot ordinarily be bodily removed from the support or supported member but is only movable in relation thereto; and arrangements 45 whereby a maximum effective shelf space is obtainable unobstructed at the ends, the means being furthermore capable of production in a simple manner of sheet metal which may be enameled or equivalently treated.
- 50 The details are capable of being widely varied but by way of example a few arrangements will now be briefly described with reference to the accompanying drawings in which Figure 1 is a side elevation, 55 and Fig. 2 a horizontal section of one of such arrangements for bookshelving for in-
- stance. Figs. 3 and 4 are similar views of another shelf supporting arrangement. Figs. 5 and 6 are also similar views of yet another modification, Fig. 7 being a view corresponding to Fig. 6 with the parts in a different position. Fig. 8 is a view similar to Fig. 4 of a further modification. Figs. 9 and 10 are diagrammatic views of other modifications and Figs. 11 and 12 are elevations at right angles to one another of a bracket supporting arrangement. As shown in Figs. 1 and 2 a guiding member *a*, which for brevity will be hereinafter referred to as a stanchion, may be employed 60 having a roll edge *b* adapted to receive one edge *c*, which may also be more or less curled, of a bracket *d* provided with a ledge *e* or lugs whereon a shelf can rest, the formation of the edges *b* and *c* aforesaid being such that they can be engaged with a rotary motion, as indicated by the arrow Fig. 2 after which the bracket *d* while free to slide longitudinally of the stanchion is prevented at the edge from moving laterally in relation thereto. The stanchion *a* is formed with a series of notches *f* which may be horizontal but are advantageously inclined upwardly and rearwardly from the roll edge *b*, while the bracket *d* is formed 70 with a series of openings *g* or notches of a different pitch which may be either arranged horizontally or inclined say in the reverse direction. In the illustration the upper edges of the openings *g* are thus inclined. With such a construction the bracket can be retained in any of the multiple adjusted positions according to the invention by means of a stud, for example 75 having heads *h*, *i* separated by a contracted neck or necks *j*, *k*, adapted to fit the recesses in both the stanchion and bracket, the heads *h*, *i* aforesaid resisting rotary movement of the bracket. The advantage of employing two contracted necks is that the 80 neck *k* acts as a head in conjunction with the head *h* to hold the stud snugly against the stanchion *a*. When the bracket *d* is raised to permit the stud to be disengaged from the notches *f*, the head *h* after said 85 disengagement can pass through the opening *g*. In order that the head *i* of the stud engaged with the bracket shall not project beyond the general plane of the bracket, the latter may be made of a joggled cross section, as clearly shown in Fig. 2.
- Or as shown in Figs. 3 and 4 a stanchion

and bracket formed with curled or roll edges b^1 c^1 similar or equivalent to those described may each be formed with a series of notches m , n of different pitch as before described, a connector o being employed which has a body portion adapted to slide within the curled edge c' of the bracket and to turn relatively thereto. A laterally projecting tongue or catch p on the body is thus capable of being entirely disengaged from both sets of notches m , n so that it can be moved longitudinally in relation to both thereof and reinserted into engagement with any pair of recesses for the time being brought into register. The combination of the notches may be such that after the catch is in engagement therewith, a slight downward movement of the bracket occurs which results in a contraction of the entrance to the notch combination that resists return movement of the catch p .

The body of the rotary and sliding catch o , p referred to may be made by twisting a strip of flat metal into a helical form as illustrated. A portion d^1 of the bracket adjacent to the roll edge c^1 may be offset in relation to the remainder thereof so that the said edge as well as that of the stanchion does not obstruct full use of the shelf, and if desired such off-set portion d' may be stamped or provided with devices such as lugs d^2 adapted to engage or coöperate with a flange a' or the like upon the stanchion a which serves as a guide for the bracket.

As a further modification, which is particularly suited to existing book cases say those of wood for example, a stanchion may be employed having a longitudinally slotted cylindrical portion notched equivalently to the roll edge of the stanchions before described, and a flanged margin by which it can be attached to the book case, the complete stanchion being let in flush with the woodwork. A hollow and similarly slotted and notched member is adapted to be inserted with an endwise movement into the said stanchion, the notches being, as in the other cases, differently pitched. The connector may be the same as, or similar to, rotary and sliding connectors already described, it also being inserted with an endwise movement into the inner hollow member and effecting the retention as set forth. The said inner hollow member may be adapted in various ways to support a shelf, or the like, being say fitted at the upper end with a projecting lug, which lug may be of a depth sufficient to prevent it entering the various notches. Or the inner hollow member may form a part of, or be formed with, an arm whereon articles may be hung for display, which arm may be movable in a horizontal plane.

The aforesaid further modification is not illustrated in the accompanying drawings

but will be understood from Figs. 5 and 6 which together with Fig. 7 show a similar modification in which however the inner hollow member referred to as well as the rotary and sliding connectors are adapted to be engaged with the stanchion without having to be inserted endwise.

In this example, a^2 is the stanchion, r a sliding member provided with a shelf supporting lug r' for instance, and o^1 a rotary and sliding connector which in this instance also is more or less tubular, the arrangement being such that whereas the parts normally occupy the position shown in Figs. 5 and 6 movement of the member r in the direction of the arrow Fig. 6 will enable it and the connector o^1 to assume the position shown in Fig. 7 where they can be disengaged from the roll edge b of the stanchion, to enable them to be removed and, it may be, replaced by a tubular member having a different form, without interfering with any other members associated with the stanchion.

From the foregoing examples other ways of carrying out the invention will readily suggest themselves it being possible in some cases to employ a connector s as shown in Fig. 8 the catch portion s' whereof is adapted to enter notches, or openings in both the stanchion a and bracket d . In a similar fashion any two members such as t u Figs. 9 and 10 having notches differently pitched may be secured against movement longitudinally relative to one another, whether the same be arranged vertically or otherwise, by connectors v Fig. 9 or v' Fig. 10 adapted to be engaged with the required notches in any suitable way.

Figs. 11 and 12 illustrate a yet further modification of the invention, w being a bracket assumed to be adjustable along the face of a flat stanchion a^2 under the control of screws x , x' x^2 . The stanchion a^2 has screw threaded holes a^3 pitched equidistantly while the bracket w has a set of holes y which the screws just fit and which are pitched equidistantly but closer together, there being in addition a slot y^1 and a slot y^2 of different lengths but the upper ends of which are of the same pitch as the holes y . The arrangement is such that assuming the bracket to be adjusted by means of the screw x passed through any one of the holes y into any screw threaded hole a^3 in the stanchion, then it will be found that one or other of the slots y^1 y^2 and in some cases both will be in register with another hole or holes a^3 in the stanchion so that the bracket w can be additionally secured by the screw x^1 or x^2 or both. In the same way also the bracket can be secured by the screws x^1 x^2 without employing the screw x .

We desire it to be understood, that, as appears from the arrangement described, by the term stanchion any appropriate mem-

ber formed with a guideway such as herein referred to is intended to be employed, whether the said member be used alone as a supporting upright or be incorporated in a 5 companion upright, which as well as the forms of bracket and other details may be analogous to those of the various known types of library or other equipments. In the same way it is obvious that the notches 10 or equivalent in lieu of being pitched uniformly throughout the entire length of the stanchions may be disposed in groups therealong.

What I claim is:—

- 15 1. Means of the kind described comprising a support having a guideway, and a series of openings spaced apart with a given pitch, a member adapted to slide along such support under the control of the guideway 20 and having a series of openings spaced apart with a different pitch, and a member adapted to enter any pair of companion openings brought into register, substantially as described.
- 25 2. Means of the kind described, comprising a support having a guideway and a series of inclined openings of a given pitch, a member adapted to slide along such support under the control of the guideway and having 30 a series of openings of a different pitch one edge of each of which makes an angle with the opposite edge of a corresponding opening in the support such as to form a region having an exit adapted to be contracted 35 and a device adapted to be inserted in such a region before the movement between the support and sliding member produces the contraction aforesaid, the inserted device being ultimately locked against accidental 40 disengagement after movement to produce the contraction is completed.
- 45 3. Means of the kind described, comprising a support having a curled edge and a series of positioning regions of a given pitch, a member also having a curled edge adapted to slide along the curled edge of the support and provided with a series of positioning regions of a different pitch, and a device adapted to slide within the innermost curled edge and to be turned to effect 50

connection between any pair of companion positioning regions for the time being in register.

4. Means of the kind described, comprising a support having a curled edge and a series of positioning regions of a given pitch, a member also having a curled edge adapted to be engaged with a sidewise movement with the curled edge of the support and to both slide and turn in the latter, such member having a series of positioning regions of a different pitch and a device adapted to slide and turn within the innermost curled edge of the member aforesaid and effect connection between any pair of companion positioning regions for the time being in register. 65

5. Means of the kind described, comprising a support having a curled edge and a series of notches of a given pitch formed in such edge, a member also having a curled edge adapted to slide longitudinally in relation to the first named curled edge and formed with a series of notches of a different pitch and a connector device adapted to slide within the innermost curled edge and having a catch adapted with rotary movement of the said device to enter any pair of companion notches for the time being in register or to be disengaged therefrom, substantially as described. 70

6. Means of the kind described, comprising a support having a curled edge and a series of inclined notches of a given pitch formed in such edge, a member also having a curled edge adapted to slide longitudinally in relation to the first named curled edge and formed with a series of reversely inclined notches of a different pitch and a connector device adapted to slide within the innermost curled edge and having a catch adapted with rotary movement of the said device to enter any pair of companion notches for the time being in register, the inclination of the notches exerting a locking action upon the connector. 85

Signed at London, England, this eleventh day of January 1921.

ARTHUR WRENN LAMBERT.
